UNITED STATES PATENT OFFICE.

HARRISON B. WALTER, OF CHICAGO, ILLINOIS, ASSIGNOR TO CHICAGO MILL AND LUMBER COMPANY, OF CHICAGO, ILLINOIS, A CORPORATION OF ILLINOIS.

BOX.

Application filed April 12, 1922. Serial No. 551,854.

To all whom it may concern:

Be it known that I, HARRISON B. WALTER, a citizen of the United States, and a resident of Chicago, county of Cook, and State of Illinois, have invented certain new and useful Improvements in Boxes; and I do hereby declare that the following is a full, clear, and exact description thereof, reference being had to the accompanying drawings, and to the letters of reference marked thereon, which form a part of this specification.

This invention relates to improvements in boxes made of fibre or paper-board or the like and consists of the matters hereinafter described and more particularly pointed out in the appended claims.

The object of the invention is to produce a collapsible box of the kind known as "top loading" as distinguished from an "end loading" box, in which the top closure is capable of such attachment to the body, when closing and sealing the box, that this attachment may be accomplished very quickly so as to result in rapid handling of the box after it is packed. The box is of especial advantage to those doing a large volume of business requiring rapid packing and handling and makes a desirable box for the packing of such articles as soap and the like.

The improved box requires a minimum of stock and may be made at low cost for material and labor. Its several advantages will appear more fully as I proceed with my specification.

In the drawings:—

Figure 1 is a perspective view of the improved box;

Figure 2 is a view representing a partial section through the box, in a plane indicated by the line 2—2 of Fig. 1;

Figure 3 is a plan view of a blank for making the body of the box; and

Figure 4 is a plan view of the blank for the ends of the box.

Referring now to that embodiment of the invention illustrated in the drawings:—10, 10 indicate the sides of the box; 11 the bottom of the box; 12, 12 the ends of the box, and 13 the top closure, comprising in this case two over-lapping flaps 13^a, 13^a.

The body of the box is made, as shown, from an elongated blank (see Fig. 3) of ap-

proximately a width equal the length of the box. This blank is cut and creased to provide the part 11 for the bottom of the box, two parts 10, 10 at each side thereof for the sides of the box and two extensions 13^a, 13^a, comprising the flaps, for the top closure 13 of the box.

The blank is creased transversely by lines 14 to define the several parts mentioned. The blank is also creased longitudinally by parallel spaced lines 15 which define the length of the several box-forming parts, except the top closure flaps 13^a, 13^a, said lines terminating at their point of meeting with the crease lines 14 defining the folding lines of the flaps 13^a, 13^a. The blank has lateral extension parts which are cut and creased to provide short folding end extensions of the two side parts and the bottom part 10^a, 10^a and 11^a. It also has lateral parts 13^b which provide end extension parts of the top closure flaps 13^a, 13^a.

The ends of the box each consist of a blank of plan area equal to the cross-sectional area of the box and of a top flap extension 12^a defined by a crease line 12^b. The flap extension 12^a of the end part 12 as well as the extensions 13^b of the top closure parts 13^a are inclined at their ends as indicated, respectively, at 12^c and 13^c.

To form the box, the blank (shown in Fig. 3) is bent into form with the bottom 11 horizontal and the sides 10, 10 in vertical relation; the blanks for the ends 12 are in succession brought into the required relation with their edges coinciding with the crease marks 15 of the main blank; and the extensions 11^a and 10^a, respectively, of the bottom and side-forming parts of the blanks are bent against them (as shown—against the outer faces of said end blanks) and are then attached together either by stapling or other well-known, familiar manner. This puts the box in condition for loading, with the flange extensions 12^a on the end vertical (but ready to be folded back) and with the top cover flaps 13^a, 13^a laid back to open up the box.

The box is then loaded. After loading, the closure flaps 13^a are turned down, the one over-lapping the other, against the flap extensions 12^a, 12^a of the ends of the box, which are folded down in the process of

folding down the top closure flaps. The top closure flaps are then stapled, sealed or attached in any convenient manner to the end flaps 12^a which stand outwardly, away from the ends of the box.

As will be apparent from the description heretofore, by reason of the flap extensions at the tops of the ends of the box, which fold outwardly and away from said ends, and by reason of the extensions on the top closure flaps which, as appears from the drawings, are adapted to close and seat upon the said flap extensions of the ends of the box, the box is capable of being sealed, stapled or otherwise permanently closed by means which operate entirely outside of and beyond the horizontal plan dimensions of the box. Thus it is possible to place boxes of the kind as they are loaded, upon a belt which will feed or present the boxes as they are loaded, to a stapling or other machine of the kind, in rapid and continuous succession, where the only requirement of the machine is that it shall secure together in two parallel spaced lines comparatively thin fibre or paper-board parts.

The folding extensions 12^a which provide the seats for the top closure and the end extensions 13^b of said top closure, provide, after they are attached together, projecting end "hand holds" or "grips" at the top of the box, which are convenient in lifting and handling the box. By reason of the inclined parts 12^c and 13^c at the ends of the respective extensions 12^a and 13^b, projecting corners are eliminated.

If desired and preferably, the top closure flaps are sealed or attached together where they overlap along a line 13^d, as by staples.

While in describing my invention I have referred to several details of construction and mechanical arrangement, it is to be understood that the invention is not thereby in any way limited except as may be pointed out in the appended claims.

I claim as my invention:—

1. A box of fibre, paper-board or the like having sides, bottom, ends and a top closure, the ends having top flap extensions 50 adapted to be folded into the plane of the top of the box, and the top closure having extensions adapted to seat upon and to be secured to the flap extensions of said ends.

2. A box made of blanks of fibre or paper-board or the like, comprising a blank cut and creased to provide a bottom, sides and a top closure flap,—the sides, bottom and top closure flap having end extensions, and blanks cut to form the ends of the box and 60 having top extension flaps; said first-named blank being folded to form the main body of the box and having the end extensions of its sides and bottom folded upon and secured to the sides and bottom parts of the 65 said end blanks, and the extensions at the top of said end blanks being adapted to be folded down to form seats in the plane of the top of the box to receive and to be attached to the extensions of the top closure 70 of the box.

3. A box of fibre, paper-board or the like made from the main blank, cut and creased to provide bottom and sides and top closure flaps, said bottom and sides and said 75 top closure flaps having end extensions;—and from blanks for the ends of the box, each having a foldable flap extension at the top; the end extensions of the bottom and sides of the main blank being adapted to be folded against and secured to the marginal parts of the end blanks, and the foldable flap extensions at the top of the end blanks being adapted to be folded down to provide seats in the plane of the top of 80 the box for the attachment of the end extensions at the ends of the top closure flaps.

In testimony that I claim the foregoing as my invention, I affix my signature this 5th day of April, A. D. 1922.

HARRISON B. WALTER.
